UNITED STATES PATENT OFFICE.

RICHARD KARKI, OF UXBRIDGE, ONTARIO, CANADA.

DESIGN FOR A RADIATOR-CAP ORNAMENT.

Application filed November 30, 1925. Serial No. 15,581. Term of patent 7 years.

To all whom it may concern:

Be it known that I, RICHARD KARKI, a citizen of Canada, residing at Uxbridge, in the Province of Ontario and Dominion of Canada, have invented a new, original, and ornamental Design for a Radiator-Cap Ornament, of which the following is a specification, reference being had to the accompanying drawing, forming a part hereof.

In the drawing:

Figure 1 is a side elevation of a radiator cap ornament showing my design;

Fig. 2 is a top plan view of the same.

I claim:

The ornamental design for a radiator-cap ornament, as shown.

RICHARD KARKI. [L.S.]
